UNITED STATES PATENT OFFICE.

PHELPS M. FREER, OF ROCHESTER, NEW YORK, ASSIGNOR, BY MESNE ASSIGNMENTS,
TO THE CONNECTICUT SHOCK ABSORBER COMPANY, OF MERIDEN, CONNECTICUT, A
CORPORATION OF CONNECTICUT.

SHOCK-ABSORBER.

987,977.

Specification of Letters Patent. Patented Mar. 28, 1911.

Application filed January 13, 1910. Serial No. 537,971.

To all whom it may concern:

Be it known that I, PHELPS M. FREER, a citizen of the United States, and resident of Rochester, in the county of Monroe and State of New York, have invented certain new and useful Improvements in Shock-Absorbers, of which the following is a specification.

This invention relates to shock absorbers, and particularly to those characterized by spring resistance.

The object of the device which is described below, is to leave the vehicle springs free to act under ordinary shocks encountered on the road, but to exert a yielding resistance to the relative movement of the body and running gear of the vehicle when a violent shock is carried to the vehicle springs.

In the drawings:—Figure 1 is an elevation partly in section, showing the shock absorber in its normal position; Fig. 2 is a section on the line 2—2 of Fig. 1; Fig. 3 is a view similar to Fig. 1, but showing the parts operatively disposed; Fig. 4 is an elevation of the device, reduced in size, showing a method of applying it to a vehicle; Figs. 5, 6, 7, and 9 are, respectively, views corresponding with the foregoing ones, showing a modified form; and Fig. 8 is a view of a detail common to both forms.

Referring first to the construction shown in Figs. 1 to 4, inclusive, the operating parts of the device are inclosed within a casing that is conveniently made in two telescoping parts 1 and 2. To the part 1 is fixed an arm 3 that extends upwardly at an angle and is adapted at its upper end for attachment to the frame A or other suitable part of a vehicle body. A similar arm 4, that is divided longitudinally (Fig. 2) so that it spans the casings 1 and 2, is adapted for attachment at its lower end to a running gear of a vehicle. In Fig. 4 the arm 4 is represented as pivoted in a bracket B that forms part of the support C for the vehicle-spring D.

Between the upper ends of the two-part arm 4 and within the casing, is a square block 5, that has in its projecting ends a series of notches 6. The arms 4 have each a series of lugs 7 that project into the notches aforesaid and so render the block 5 immovable with respect to the arms 4. A bolt 8 extends through both the block and the arm,

and serves to maintain the engagement of the lugs and the notches, as well as to hold the parts 1 and 2 of the casing together.

Surrounding the block 5 and fitting closely to its sides is a disk 9 that has a symmetrical but partially eccentric contour on its periphery (Fig. 8). A series of flat springs 10 are set within the casing 2, with their ends resting in pockets 11 that are offset in its rim. These springs are adapted to lie against the periphery of the disk 9, but in the present instance chafing strips 12 are shown as lying between the springs and the disk to receive the wear that would otherwise come on the latter. These strips may be easily and cheaply replaced by new ones when worn thin.

The disk 9 is movable with the arm 4, because engaged by the block 5, while the casing 1, which is rigidly connected with the arm 3, controls the movement of the springs 10 around the said disk. These portions 13 of the periphery of the disk 9 that normally bear against each of the springs 10 (Fig. 1) are concentric with the bolt 8 for a short distance on either side of a line drawn from the center of the bolt to the center of the spring, at right angles to the latter. Between these portions 13 of the disk 9 its contour is eccentric to the pivot-bolt 8. Said eccentric portions 14 have longer radii than the circle of which the portions 13 are arcs, and they extend some distance outside of said circle. These portions 14 thus constitute a series of cam faces equal in number to the springs 10. When the disk 9 and the springs 10 are given an opposite rotary movement, said faces 14 bear against the strips 12, and force the said springs toward the rim of the casing. The ends of the springs are immovable, as they are retained in the pockets 11, and so the partial rotation of the disk 9 results in bending the springs at their middle, as shown in Fig. 3. The farther the disk is turned, the more the springs will be bent, and the greater will be the force required to bend them. As the bending of the springs occurs only after the eccentric portions 14 have begun to press against them, it follows that the disk 9 may be turned with comparative freedom either way from the position shown in Fig. 1, for some distance since the concentric portions 13 are of no effect as regards the movement

95

of the springs, as they cannot exert a leverage on the latter. This construction renders the springs 10 ineffective when the relative movement of the vehicle body and the running gear thereof is within the ordinary working limit of the vehicle springs D, but when this movement becomes extreme, as happens when the vehicle encounters a severe hump in the road, the disk 9 is turned 10 in one direction, by the upward movement of the arm 4, while the casing parts 1 and 2, with the springs 10, are turned so far in the opposite direction, by the downward movement of the arm 3, till the portions 14 are 15 brought beneath the springs 10 and bend them as shown in Fig. 3.

It will be noted from the foregoing that the rubbing contact of the disk and springs does not serve to oppose the movement of 20 the parts and is merely incidental to the movement of the parts after they have been brought into relative engagement. Again, the action of the parts is practically frictionless until the eccentric portions 14 begin 25 to bend outwardly the strips 12, and so the normal action of the vehicle springs D is not impeded in the least.

In the construction shown in Figs. 5 to 9, inclusive, the lugs 7^a that enter the notches 30 6^a in the square block 5^a, project from a bracket 4^a that is attached to one of the vehicle parts (in the drawings it is shown attached to the vehicle body), thus dispensing with one of the arms before described. 35 In this construction the arm 3 that is fixed to the casing 1 is preferably connected with the support C for the vehicle springs by a link 15. The operation is the same as before described.

40 What I claim is:

1. In a shock absorber comprising two relatively rotatable parts, one part comprising a cam, the other part comprising a

case surrounding and supporting said cam, a lever arm carried by each part and projecting laterally therefrom, said cam having a plurality of high points, a plurality of springs arranged to be flexed by the rotation of said cam, said springs being carried by said case and a connection between the 45 cam and its lever arm comprising an angular block extending concentrically into the cam, said cam having an angular recess to receive said block wherein said block is held against rotation independently of the cam, 50 and means for connecting said lever to the outer end of said block.

2. In a shock absorber, two relatively rotatable parts, one a cam, the other a case, said cam having a plurality of high points, 55 a plurality of springs held within the case and arranged tangentially to said cam for operation thereby, said case having pockets formed therein for the reception of the ends of the springs, the back of said springs being 60 separated from said case excepting at their ends whereby said springs may be flexed.

3. In a shock absorber, a spring carrying case comprising two telescopic members having laterally offset portions forming integral pockets to receive the ends of the springs, a plurality of springs within said case, the ends of said springs being seated in said pockets, a rotatable cam within the case and between the springs, said cam having a plurality of high points, and means for connecting said parts to a vehicle whereby the relative movement of the vehicle body relatively to the axle thereof will impart a relative rotary movement of said cam 75 and spring carrying element.

PHELPS M. FREER.
